MACHINE PRESS

Robert M. Cook, Tuscaloosa, Ala.

Application May 14, 1946, Serial No. 669,692

7 Claims. (Cl. 100—266)

1

This invention relates to shop equipment, and more particularly to power-operated tools, including power presses, drill presses, and the like.

Various types of machine and repair shops frequently have use for a press to disassemble or assemble, bend or straighten or otherwise operate upon machine parts. Various types of presses, usually referred to as arbor presses, are now used in machine shops and large repair shops but these are all specialized and expensive machines of limited utility. Such machines are economically unavailable to the smaller shops and garages because the amount of work requiring a press is not sufficient to justify the cost of a conventional arbor press and the amount of space it occupies. It is therefore the present practice with owners of smaller shops and garages to carry their press work to a larger shop where a press is available. This results in a large amount of lost time and additional expense.

It is therefore among the objects of the present invention to provide an improved machine press of economical construction which requires a minimum amount of space and in which the more expensive components are standard units that have utility in addition to their use as press components.

A further object resides in the provision of an improved power operated machine press in which the power components, such as the electric driving motor, are useful in capacities other than as press components and may be used for other purposes either while attached to the press or when removed therefrom.

Another object resides in the provision of a durable and economical machine press component which may be operatively associated with other components of conventional shop or garage equipment to provide either a manually operated or power operated machine press.

A further object of the invention is to provide a simple, inexpensive, press of light weight, which may be used with or without its source of power, and its source of power may be operated independently of the press.

Further objects and advantages of the invention will be apparent from the following description taken in conjunction with the accompanying drawings, wherein:

Fig. 1 is a side elevational view of the entire machine;

Fig. 2 is an end elevational view of the upper portion of the machine;

Fig. 3 is a partial fragmentary elevational view partly in section showing the adjustable link con-

necting the adjustable eccentric to a hydraulic jack;

Fig. 4 is a section taken on line 4—4 of Fig. 3 showing the ball and socket joint in the jack handle; and,

Fig. 5 is a section on line 5—5 of Fig. 3.

With continued reference to the drawings and particularly to Fig. 1, a rigid base or table top 10 is supported by suitable means such as legs 11, disposed one at each corner of the substantially rectangular base. In order to reinforce the support, the two legs at each end of the base may be secured together by a suitable tie member in the form of an angle iron 12. The base 10 is formed of suitable structural members, such as deep web I beams and has secured thereto an upright standard 13, which may be conveniently provided by utilizing two channel irons disposed back to back. The lower ends of the channel irons rest upon the I beams of the base and are rigidly secured thereto by suitable means such as gusset plates 14. At the upper end of the standard 13, an arm 15 extends outwardly toward the adjacent end of the base and may be formed by a pair of angle iron members secured together flange to flange and welded or otherwise rigidly secured at one end to the upper end of the standard 13. A shaft 16 is slidably mounted in a journal 17 secured in the outer end of the arm 15 and is connected through suitable means such as link 18, pivot pins 18' and collar 19 with a looped spring 20 which resiliently urges the shaft 16 upwardly relative to the arm 15. The collar 19 is adjustable lengthwise of the shaft and is held in adjusted position by suitable means such as the wing nut set screw 21. Fixed on the lower end of the shaft 16 there is a collar 22 which is detachably secured to a press head 23. Various press heads may be attached to the collar 22 to accommodate the press to the shape of any particular part on which it is desired to exert pressure by the machine.

A lever 25 of the first class is fulcrumed intermediate its length to the standard 13. This fulcrum may conveniently be provided by placing a U-shaped clip or strap 26 over the lever and providing it with apertured end portions extending below the lever through which extends a pin 27 which also extends through a suitable aperture in the standard 13.

The lever 25 may be conveniently provided by welding together two pieces of channel iron placed with the edges of their flanges in contact.

At one end the lever 25 is tapered, as indicated at 28, and the lower flanges of the channel

members are cut away to permit the shaft 16 to pass therethrough. A pair of pressure pads 29 and 30 are secured to the under side of the lever and rest upon abutments formed by the top of the collar 22, one at each side of the shaft 16. These pads are curved on their bottoms to provide a rolling and sliding contact with the top of the collar as the lever swings about the fulcrum 27.

At its opposite end the lever 25 has secured thereon a U-shaped clip or strip 32 having downwardly projecting apertured end portions through which a pin 33 extends to pivotally secure a saddle 34 to the lever end.

It is obvious from the description so far that upward pressure on the saddle 34 will swing the lever about the fulcrum 27 and force the collar 22 and press head 23 downwardly and that when the pressure on the saddle is released the spring 20 will move the shaft 16 together with the collar 22 and press head 23 upwardly. This upward movement of the collar 22 will swing the lever back to its original position. It will be noted that shaft 16 extends well above the lever 25 and arm 15, and shaft 16 is free to move downwardly relative to said lever whereby the top of said shaft may be struck to exert an additional or an independent force to the work.

A conventional hydraulic jack 35 is placed on the top of the base 10 at the corresponding end of lever 25 and the adjustable stem 36 is moved until its upper end contacts the saddle 34. The jack handle 37 extends diagonally across the base 10 and terminates at one side of the base intermediate the length thereof. United States patent to Shannon, No. 1,990,004, discloses a jack of this type with the conventional piston and valves for raising and lowering the same.

A belt pulley 38 is rotatably supported below the base by suitable bracket 39 provided at its lower end with a journal for the pulley shaft 40. An adjustable length link 41 is operatively connected at its lower end to the pulley 38 and at its upper end to the outer end of the jack handle 37. The link 41 is rendered adjustable by the screw threaded connection between the lower portion and upper portion thereof. The connection between link 41 and handle 37 is preferably provided by a ball and socket connection held in operative position by suitable means such as the screw plug 42 engaging a block 70 which engages a ball 71 which engages another block 72 which is urged outwardly by a spring 73; by removal of screw plug 42 the link can be readily disconnected from the handle and the handle operated manually when desired. This type of connection is conventional and is commonly employed in automobile steering connections and in shock absorber links. The connection between the link 41 and the pulley 38 may conveniently include a radial slot 44 in the pulley which receives a pin bolt 43 rotatably connected with the lower end of the link. The pin may be adjusted along the length of the slot by releasing nut 74 and moving bolt 43 to vary the effective lever arm between the axis of the pulley shaft and the axis of the bolt 43, thereby varying the force applied to the jack handle upon rotation of the pulley.

A bracket 45 is secured to the end of the support or base 10 adjacent the pulley 38, which bracket may conveniently comprise a generally horizontal table portion 46 and inclined supporting brackets 47. A drill press, generally indicated at 48, is mounted on the support 45 in 75

a manner such that it is completely operative as a drill press at any time when it is desired to operate the machine press. This drill press includes a flat base 49 supported at one side thereof, an upwardly extending stem or standard 50 upon which is slidably mounted a bracket 51 carrying the electric motor 52. A handle 53 is pivoted intermediate its ends on the bracket 51 for moving the bracket up and down the standard 50, the handle being connected to the bracket through suitable means such as a link connected to the lower end of the handle and to the collar 54 which may be adjustably fixed on the standard 50. Compression spring 55 is provided to normally maintain the bracket 51 in uppermost position.

When it is desired to drive the machine press, a pulley shaft 56 is secured at its upper end in the drill chuck 57 of the drill press and passes downwardly through a suitable opening in the base 49. The lower end of the shaft 56 is supported in a suitable bearing 58 which may be secured to the brackets 47 and carries on its end portion below the bearing 58 a belt pulley or sheave 59. A belt 60 connects the pulley 59 with the jack operating pulley 38. With this arrangement, when the motor switch 61 is operated to energize the motor the drill press motor drives the pulley 38, which in turn operates the link 41 and the jack handle 37 to actuate the pump of the hydraulic jack.

When the jack is provided with a conventional reversing control 62 an extension 63 leads from the control through an apertured collar 64 in the standard 13 to place the reversing control lever 65 in convenient reach of a person operating the machine press.

It will be obvious to those skilled in the art that various changes may be made in the invention without departing from the spirit and scope thereof and therefore the invention is not limited by that which is shown in the drawings and described in the specification but only as indicated in the appended claims.

What is claimed is:

1. A machine press comprising a base; an upright standard secured at its lower end to said base; a lever fulcrumed intermediate its ends on said standard; a generally horizontal arm secured to the top of said standard and extending along said lever substantially to the corresponding end thereof; a substantially vertical shaft slidably supported in the outer end of said arm and extending past the corresponding end of said lever; a collar on said shaft below said lever; pressure pads on said lever contacting the top of said collar; a press head detachably secured to the lower end of said collar; a jack on said support adjacent the opposite end of said lever; a saddle on said opposite end portion of the lever operatively connecting the lever with the jack; a pulley supported on said base and operatively connected with said jack; and a motor driven machine associated with said base adjacent said pulley and drivingly connected with said pulley whereby operation of said motor will operate said jack and said vertical shaft.

2. A machine press as defined in claim 1 wherein the connection between said pulley and said jack is disconnectable for manual operation of the jack.

3. A machine press as defined in claim 1 wherein the connection between said pulley and said jack is adjustable to vary the drive ratio between said motor and said jack.

4. A machine press comprising a base, a standard positioned intermediate the ends of said base and extending upwardly from and secured to said base, a lever pivotally mounted intermediate its ends on said standard, an arm extending toward one end of said lever mounted on said standard above said lever, a shaft slidably mounted in the free end of said arm for movement toward and away from said base, a collar mounted on said shaft below said lever whereby said collar moves downwardly when said one end of said lever is moved downwardly, and a conventional lifting jack positioned on said base and engaging the other end of said lever for raising said other end of said lever and thereby forcing said shaft downward to exert a force toward said base, the upper end of said shaft extending above said arm and said lever.

5. A machine press comprising a base, a standard positioned intermediate the ends of said base and extending upwardly from and secured to said base, a lever pivotally mounted intermediate its ends on said standard, an arm extending toward one end of said lever mounted on said standard, a shaft slidably mounted in the free end of said arm for movement toward and away from said base, a collar mounted on said shaft below said lever whereby said collar moves downwardly when said one end of said lever is moved downwardly, and a conventional lifting jack positioned on said base and engaging the other end of said lever for raising said other end of said lever and thereby forcing said shaft downward to exert a force toward said base, the upper end of said shaft extending above said arm and said lever.

6. A machine press comprising a base, a standard positioned intermediate the ends of said base and extending upwardly from and secured to said base, a lever pivotally mounted intermediate its ends on said standard, an arm extending toward one end of said lever mounted on said standard, a shaft slidably mounted in the free end of said arm for movement toward and away from said base, an abutment on said shaft below

5 said lever and engageable with said one end of said lever whereby said shaft moves downwardly when said one end of said lever is moved downwardly, a collar adjustably mounted on said shaft, and spring means reacting between said arm and said collar for urging said shaft upwardly.

10 7. A machine press comprising a base, a standard positioned intermediate the ends of said base and extending upwardly from and secured to said base, a lever pivotally mounted intermediate its ends on said standard, an arm extending toward one end of said lever mounted on said standard, a shaft slidably mounted in the free end of said arm for movement toward and away from said base, an abutment on said shaft below said lever and engageable with said one end of said lever whereby said shaft moves downwardly when said one end of said lever is moved downwardly, a hydraulic lifting jack for moving the other end of said lever upwardly, a motor, and adjustable driving connections between said motor and said jack for varying the drive ratio between said motor and jack.
